(57) **CLAIM**

The ornamental design for a sofa, as shown and described.

DESCRIPTION

FIG. 1 is a right front perspective view of a sofa showing my new design;

FIG. 2 is a left elevational view thereof, the right side elevation being a mirror image;

FIG. 3 is a top plan view thereof;

FIG. 4 is a left rear perspective exploded view, shown in the reclined position thereof;

FIG. 5 is a left rear perspective view, shown in the non-reclined position thereof;

FIG. 6 is a left rear perspective partially exploded view, shown in the reclined position thereof; and,

FIG. 7 is a front elevational view, shown in the non-reclined position thereof.

The broken lines in the figures are for the purpose of illustrating portions of the sofa, which form no part of the claimed design.
